UNITED STATES PATENT OFFICE.

ELNATHAN COLE, OF LOS ANGELES, CALIFORNIA, ASSIGNEE TO COLE MANUFACTURING COMPANY, A CORPORATION OF CALIFORNIA.

FLUE CONSTRUCTION.

1,264,016.

Specification of Letters Patent. Patented Apr. 23, 1918.

Application filed September 12, 1916. Serial No. 119,767.

To all whom it may concern:

Be it known that I, ELNATHAN COLE, a citizen of the United States, residing at Los Angeles, in the county of Los Angeles and 5 State of California, have invented a new and useful Flue Construction, of which the following is a specification.

My invention relates to flue construction, and the principal object of the invention is 10 to provide a novel flashing means for making the flue water-tight where it passes through a roof. There are coming into general use a large number of forms of small gas heating devices for which small chimneys or flues must be provided in the construction of buildings. A convenient and 15 economical method of constructing gas flues or chimneys is by the use of round or rectangular tubes formed of pottery, stone- 20 ware, cement, or the like. Where such flues pass through a roof, it is necessary to make a water-tight joint with the roof, so that 25 there will be no leakage around the flue.

My invention relates particularly to the 25 means for making such a water-tight joint.

In the drawings, which are for illustrative purposes only:

Figure 1 is a cross section through a portion of a roof and a portion of a rectangular flue illustrating my form of construction.

Fig. 2 is a similar view through a section of a roof and a section of a round flue.

Fig. 3 is a cross section on a plane represented by the line 3—3 of Fig. 1, looking in the direction of the arrows.

Fig. 4 is a cross sectional view on a plane represented by the line 4—4 of Fig. 2, looking in the direction of the arrows.

40 In the construction of flues, tubes 11 are employed, these tubes being beveled off as shown at 12 to suit the upper surface of the roof 13 through which the flue is to pass. An upper tube 14 is then beveled off to 45 form a continuation of the tube 11, and a metal sleeve 15 is placed inside the tubes 11 and 14 so as to hold them in alinement and to assist in the cementing operation to be described further. Before the upper tube 50 14 is slipped in place over the sleeve 15, a flashing plate 16 is placed over the sleeve 15, this flashing plate being covered at its

upper surface by roofing material 17 and resting along its lower edge on roofing material 18. The flashing plates 16 are provided with perforations 19, these perforations coming centrally in the wall of the tubes 11 and 14 when these tubes are placed together. Cement is placed under the plate 16 and on top of the plate 16 before the tubes 11 and 14 are forced into place, this cement being excluded from the interior of the flue by the sleeve 15, so that a smooth joint through the flue is provided at all times. The cement is allowed to harden. 65 The cement below the plate 16 and the cement above that plate are joined together by cement members in the perforations 19.

I claim as my invention:

1. A construction for making a water-tight junction between a flue and a roof comprising a lower flue structure below the roof, said structure being beveled off flush with the upper surface of the roof; an upper flue structure resting on said lower flue structure; a flashing resting on the roof and projecting between said upper flue structure and said lower flue structure; and a body of cement binding said upper flue structure, said lower flue structure, and said flashing together, said flashing being provided with openings through which said body of cement extends.

2. A construction for making a water-tight junction between a flue and a roof comprising a lower flue structure below the roof, said structure being beveled off flush with the upper surface of the roof; an upper flue structure resting on said lower flue structure; a sleeve inside of and joining said upper flue structure with said lower flue structure; a flashing resting on the roof and projecting between said upper flue structure and said lower flue structure; and a body of cement binding said upper flue structure, said lower flue structure, and said flashing together.

3. A construction for making a water-tight junction between a flue and a roof comprising a lower flue structure below the roof, said structure being beveled off flush with the upper surface of the roof; an upper flue structure resting on said lower flue structure; a sleeve inside of and joining said

upper flue structure with said lower flue structure; a flashing resting on the roof and projecting between said upper flue structure and said lower flue structure; and a body of cement binding said upper flue structure, said lower flue structure, and said flashing together, said flashing being provided with

openings through which said body of cement extends.

In testimony whereof, I have hereunto set my hand at Los Angeles, California, this 31st day of August, 1916.

ELNATHAN COLE.
